CLAIM

The ornamental design for a head positioner, as shown and described.

DESCRIPTION

FIG. 1 is a perspective view of a head positioner showing our new design;

FIG. 2 is a top view thereof;

FIG. 3 is a bottom view thereof;

FIG. 4 is a left view thereof;

FIG. 5 is a right view thereof;

FIG. 6 is a rear view thereof; and,

FIG. 7 is a front view thereof.

1 Claim, 7 Drawing Sheets
